TUBULAR SECTION FOR LAMP STANDARDS

Sam Bucholtz, New York, N. Y.

Application February 12, 1954, Serial No. 28,982

Term of patent 14 years

(Cl. D48—7)

To all whom it may concern:

Be it known that I, Sam Bucholtz, a citizen of the United States of America, and a resident of the city of New York, in the county of Bronx and State of New York, have invented a new, original, and ornamental Design for a Tubular Section for Lamp Standards, of which the following is a specification, reference being had to the accompanying drawing, forming a part thereof.

Fig. 1 is a front elevational view of a tubular section for lamp standards showing my new design;

Fig. 2 is a top plan view; and

Fig. 3 is a sectional view taken through line 3—3 of Fig. 1.

The ornamental peacock design on the cylindrical portion of the unit shown in Fig. 1 repeats three times around the circumference of the said cylindrical portion of the unit and the flower and leaf design around the wide lower portion of the unit repeats four times around the circumference of the said lower portion of the unit.

I claim:

The ornamental design for a tubular section for lamp standards, substantially as shown and described.
